UNITED STATES PATENT OFFICE.

WALTER A. RUHE AND HENRY S. BURBANK, OF PHILADELPHIA,
PENNSYLVANIA.

ACETYLENE-GAS APPARATUS.

SPECIFICATION forming part of Letters Patent No. 600,177, dated March 8, 1898.

Application filed April 5, 1897. Serial No. 630,714. (No model.)

To all whom it may concern:

Be it known that we, WALTER A. RUHE and HENRY S. BURBANK, citizens of the United States, residing at the city of Philadelphia, in 5 the county of Philadelphia and State of Pennsylvania, have invented certain new and useful Improvements in Acetylene-Gas Apparatus, of which the following is a specification.

Our invention has relation to apparatus for 10 generating and supplying what is known as "acetylene gas" for utilization.

The principal object of our invention is to provide a comparatively simple, durable, and efficient apparatus for generating and storing 15 acetylene gas and for supplying the same for illuminating and other purposes.

Our invention, stated in general terms, consists of an apparatus for generating and supplying acetylene gas constructed and arranged in substantially the manner herein-after described and claimed.

The nature and general features of our invention will be more fully understood from the following description, taken in connection 25 with the accompanying drawings, forming part thereof, in which—

Figure 1 is a side elevational view of a plant embodying the features of our invention. Fig. 2 is an end elevational view of the same. 30 Fig. 3 is a view, partly in elevation and partly in section, of the water-supply, with its connections to a retort, embodying certain features of our invention. Fig. 4 is a top or plan view of Figs. 1 and 2. Fig. 5 is a side elevational view looking to the left in Fig. 1, showing the device connected with the retort and water-supply and with the receiver or gasometer for controlling the cutoff of the water-supply and thereby the flow of gas when the receiver or gasometer contains its full quota of 35 gas distributing or discharging therefrom. Fig. 6 is an end view, partly in section, of said device. Fig. 7 is a top or plan view of the valve connections from the retorts, with the water-supply, showing the pipe connections to the receiver or gasometer and the means for cutting off manually the flow of the gas from each retort, as well as the flow of water into each of them. Fig. 8 is a view, partly in elevation and 45 partly in section, of the valve connection of Fig. 7. Fig. 9 is a perspective view of a safety

device for preventing the opening of one of the retorts while the other is generating gas, and Figs. 10 and 11 represent views in plan and section of the lever for alternately cutting out 55 the retorts, as well as the flow of gas to the receiver or gasometer.

Referring to the drawings, A is the receiver or gasometer, provided with a dome a^1 and an offtake a^1 , having connected with the same a pressure gage or register a^2 of any preferred construction.

a^3 is a bracket secured to the roof of the dome a^1 and provided with a bearing a^4 , through which extends a weighted rod a^5 . To the side 60 of the gasometer A is provided a similar bracket a^6 with a bearing a^7 .

B is an electric indicating or signaling device provided with contacts b and b' , respectively connected with the gasometer A and the dome a^1 thereof, as illustrated in Fig. 1 of the drawings. This device B is provided with wires 12 and 13 from a battery 14, in which circuit is included a buzzer, bell, or other sounding device b^2 , whereby when the gas in 70 the gasometer or receiver A has become low or exhausted the two contacts will be brought into a position to establish the circuit from the battery 14, and thereby to ring the bell or buzzer b^2 to indicate that the gas-supply is 80 in fact exhausted or that the amount of gas in the receiver is becoming low or that the water of an elevated tank is not supplying the retort to aid with the carbid or acetylid in producing gas for being supplied to the 85 gasometer A for use therefrom.

C is an elevated water-supply consisting of a tank provided with a tube c^1 extending downward therefrom into a standard or base c^1 . Connected therewith is a nipple c^2 , provided 90 with an elbow c^3 , with which is connected a vertical pipe c^4 , provided with a valve c^5 , adapted to be operated so as to cut off the water-supply to the retort when required. This pipe c^4 , by means of a U-shaped pipe connection c^6 , extends into the upper part of the retorts D and D'. Each of the retorts is provided therein with a channel d , extending into the body of each cap or cover d^2 of the retorts. Each cap or cover is provided with a pipe or tube d^3 , communicating with the channel d and set, preferably, at a downwardly-project-

ing angle extending to about the center in the upper part of the retort, as clearly illustrated in Fig. 3 of the drawings, for supplying water from the top of the retort onto the acetylid 5 or carbid d^4 , mounted in the retort—for example, in the manner illustrated in Fig. 3. It will be seen from said Fig. 3 that the pipes c and c^4 , with the base c' , provide the means whereby a water seal may be established between the elevated tank C and the retorts D and D' to prevent undue waste or dissipation of the gas in the retort in use, because the weight and quantity of water always maintained in the said pipes and base will be sufficient to prevent the gas in the retort from escaping through the water, so that the supply of generated gas will thereby be only through the pipe connections with the gasometer A. The removable caps or covers d^2 of the retorts are suitably gasketed at d^5 to the same and secured to position thereon by means of bolts d^6 and nuts d^7 and also by means of spanning-clamps d^8 , provided with jam-bolts d^9 with key-heads d^{10} , for example, as illustrated in Figs. 1 and 2. In the bottom of each retort is provided an outlet d^{11} , having a stop-cock d^{12} , whereby the interior of the retort may be cleaned out, as required.

d^{13} is a gas-pipe connecting the retort D with the retort D' and having an interposed plug-valve d^{14} . d^{15} is the downward right-angular extension of said gas-pipe at the bottom provided with a stop or blow-off cock d^{16} , and the angular extension of said pipe is secured into the lower portion of the gasometer A, as clearly illustrated in Fig. 1 of the drawings. The valve c^5 in the water-supply pipe to the retort D or D' has connected therewith a lever or arm a^{10} , embracing the vertical rod a^5 and sliding in the guides or bearings a^4 and a^7 , connected with and extending from the dome a and gasometer A. Adjustably mounted on the rod a^5 is a sleeve or collar e , carrying one end of a spiral spring e^4 , the other end of which is connected with the arm or lever a^{10} . Mounted on the vertical pipe c' is an adjustable collar e^2 , provided with a slanting or depending finger e^3 , adapted to limit the range of upward movement of the arm or rod a^{10} as the dome a rises by the flow of gas from one of the retorts D or D' into the gasometer A prior to the discharge of the same from the latter through the pipe a' , under regulation for utilization as an illuminant or for other analogous purposes. The valve d^{14} of the pipe d^{13} , connecting the retort D with the retort D' , is inclosed in a housing d^{18} , and extending through this housing is a rod d^{19} , carrying a cam d^{20} . To the upper end of this rod d^{19} is secured a lever d^{21} , the free end of which engages the key d^{10} of the jam-bolt d^9 . The cam d^{20} normally rests against a head or strip f , formed, preferably, integral with a connecting-rod F, the opposite end of which connecting-rod engages a plug-valve g , mounted in a housing g' , and which valve is connected with the U-shaped water-pipe connection c^6 .

The connecting-rod F at the respective ends of the same, engaging the plug-valves d^{14} and g , is operated by a lever h , fitted to said rod F and carrying a disk or collar h' . The lever h is adapted to be released from the connecting-rod F through either the opening g^2 or g^3 of the housing g' , when in the position illustrated in Figs. 4, 7, 8, or 11, to permit of the free flow of fluid to one or the other of the retorts D or D' ; but when the lever h is turned but ninety degrees or into a vertical position the disk or collar h' , mounted thereon, will prevent the removal of the lever h through the slit g^4 in the housing g' , being an intermediate position of the same, and while in such position the water-supply to both of the retorts, as well as the gas-supply from said retorts, will be cut off to the gasometer A. In this intermediate position of the lever h the head f of the connecting-rod F occupies the position indicated by the dotted lines in Fig. 9, in which position the head f is clear of the cam d^{20} , connected with the lever d^{21} . In this position it will be readily understood that the cam d^{20} and lever d^{21} may be shifted or turned to permit of the removal of the cap or cover of the retort, as illustrated in Fig. 4, for refilling or any other required purpose. The safety attachment, comprising the head or strip f , cam d^{20} , and lever d^{21} , connected with the housing of the valve d^{14} , is provided for the purpose of enabling the inexperienced or others to readily determine which cap or cover of the retorts is to be removed for filling, due to the exhausting of the matter adapted to generate gas therein, because said lever d^{21} , while the particular retort is in use, will be connected with the other retort not in use or containing matter sufficient upon the supply of water to the same to permit of the generation of gas therein for supplying to the depleted gasometer A. When the lever h is in its normal position and is turned to an opposite position—say about one hundred and eighty degrees—the lever d^{21} will be locked in such position as is illustrated in Fig. 9 by the cam d^{20} , engaging the head or strip f of the connecting-rod F, and thereby it will be impossible to operate the said lever d^{21} , and thus the cap or cover of the retort with which the said lever is connected cannot be removed until the lever is released.

The operation of the apparatus hereinbefore described is as follows: With the members of the apparatus as indicated in full and dotted lines in Figs. 1, 2, and 4 the retort D is in use making gas and supplying to the gasometer A, and the gas is being withdrawn from the gasometer through the offtake or pipe a' , under due regulation of the pressure gage or register a^2 , for utilization. If the gas-supply, as well as the water-supply, is to be cut off, the lever h is turned so as to assume a vertical position of about ninety degrees to that which it occupies in Fig. 4; also, when the retort D ceases to generate gas; but any gas remaining in a retort will be supplied to

the gasometer until withdrawn in sufficient quantity to cause the contacts b and b' to establish the battery-circuit 12 and 13 with the buzzer b^2 or other signaling device to apprise 5 the operative that the supply of gas in the gasometer is becoming low or is being exhausting, when by turning the lever d^{21} to a position opposite to that which it occupies in Fig. 4 the retort D' may be placed in condition 10 for generating gas, so as to supply the gasometer therewith, and the other retort D will then be cut off both from the water-supply C and the gasometer A . By removing then the clamp d^8 and bolt and nut from the 15 cap or cover of the same it may be refilled and placed in a condition upon the depletion of the retort D' of the matter capable with water of making gas of being brought into use by shifting the lever d^{21} into a position 20 opposite to that which it occupies in Fig. 4.

Among the advantageous features of our invention may be mentioned that the arrangement of the apparatus is such as that gas in the retorts may be safely and reliably made 25 and supplied to the gasometer for use especially in house consumption, with the location of such a plant in the cellar of the house and used without fear by the exercise of reasonable care of any explosions or accidents arising 30 therefrom, because of the ability by the arrangement of the members of the apparatus when the gasometer contains substantially its fully quota of gas to automatically cut off both elements adapted to generate the gas, 35 and also is the arrangement of the apparatus such as that when the supply is low in the gasometer to automatically signal to the operative what is necessary to be done to expeditiously replenish the supply and with perfect 40 safety, even if the apparatus is handled by an inexperienced person, and, furthermore, without waste or dissipation of the gas due to the water seal established between the water-supply and the retorts and the inability 45 to refill a retort by removing the cap or cover until the particular retort of the series is entirely cut off from the water-supply and gasometer and the retort generating the gas and supplying the same to the gasometer. 50 It will be manifestly obvious to those skilled in the art to which our invention appertains that, as to details, modifications may be made without departing from the spirit and scope of our invention, and hence we do not wish to 55 be understood as limiting ourselves to the precise construction and arrangement of all the parts as hereinbefore described and illustrated; but,

Having thus described the nature and objects of our invention, what we claim as new, 60 and desire to secure by Letters Patent, is—

1. In an apparatus of the character described, a retort wherein a substance to be reduced is contained, a movable cap secured to the top of said retort, a channel formed in 65 said cap and having a pipe leading therefrom to the interior of said retort, a channel formed in the retort immediately below the channel in said cap, a water-reservoir elevated above the top of said retort, a hollow standard in 70 communication with and supporting said reservoir, and a pipe connection leading from the base of said standard to the channel in the body of said retort, whereby when the cap of the retort is turned the same is adapted 75 to establish or cut off communication with said channels, substantially as and for the purposes described.

2. In an apparatus of the character described, a retort or series of retorts, a pipe 80 supplying said retort or retorts with water, a valve interposed in said pipe, a lever or arm adapted to operate said valve, a vertical rod embraced by the free end of said lever, a spring connecting the free end of said lever 85 with said arm, a stop located on said rod and adapted to depress the lever against the tension of said spring, a stop located on said water-pipe to limit the upward motion of said lever, and a gasometer having a movable 90 dome adapted to actuate said vertical rod, substantially as and for the purposes described.

3. An acetylene-gas apparatus, comprising a gasometer, retorts connected with each other by a pipe and plug-valve connections, a water-supply connected with said retorts by pipe and valve connections and said valves enclosed in housings and connected with each other by a rod and adapted to be operated in unison by a lever to cut off the water-supply 100 from one retort to the other and the gas therefrom to the gasometer, a lever adapted to actuate a cam against the housing of one of said valves to prevent removal of a cap or cover of one of said retorts while in use and 105 until the retort is cut out as well as the water-supply thereto, substantially as and for the purposes described.

In testimony whereof we have hereunto set our signatures in the presence of two subscribing witnesses.

WALTER A. RUHE.
HENRY S. BURBANK.
